ATTORNEY

UNITED STATES PATENT OFFICE

HENRY M. NICHOLLS, OF CHICAGO, ILLINOIS, ASSIGNOR TO AMERICAN CAN COMPANY, OF NEW YORK, N. Y., A CORPORATION OF NEW JERSEY

CONTAINER

Application filed May 31, 1928. Serial No. 281,664.

My invention relates in general to sifter top containers and more particularly to self-closing sifter top containers of the type shown in the pending application of Stanley H. 5 Lindgren, Serial No. 710, 235, filed May 1, 1924, and is an improvement upon the same.

This improvement contemplates the provision of a gasket or liner between the container body and the sifter slide member, which prevents leakage or sifting of the contents of the 10 container except through the sifter openings upon manipulation of the sifter slide.

The invention further contemplates the provision of a gasket or liner which not only 15 stops leakage between itself and the sifter slide with which it contacts but also prevents leakage between the sifter slide and the outer top member by reason of the spring-like pressure it exerts against the slide member. This 20 yielding pressure keeps all parts in tightly assembled relation, which is a desirable advantage when filled containers are roughly handled and knocked about in storage and transportation.

25 A further object of the invention is the provision of a sifter top gasket or liner which is formed of inexpensive material, which requires a very simple gasket seat or support and which is readily assembled with the other 30 sifter top parts.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a sifter top can in which my invention is embodied; 40 Fig. 2 is a perspective view of the several parts of my sifter top construction, showing these parts in unassembled superposed relationship;

Fig. 3 is a top plan view, partially broken away for better illustration of the assembled sifter top; and

Fig. 4 is a partial vertical section through the assembled sifter top.

The self-closing sifter container shown in 50 the drawings comprises a cylindrical body 11

of metal or fibre having a metal bottom end 12 seamed, crimped, or otherwise permanently secured thereto.

The sifter top construction comprises, in general, an inner top member 13, a gasket 14, 55 a sifter slide 15 and an outer top member 16 (see Fig. 2 where all of these parts are shown in unassembled superposed relationship).

The inner top member 13 has a flange 17 crimped, seamed or otherwise permanently secured to the top edge of the container body 11, 60 a vertical annular wall 18 disposed within the mouth of the container body and substantially parallel with the body wall, an annular channel or sunken part 19, a central sloping and raised part 20 which terminates in a horizontal annular recess 21, which is adapted to form a seat for the gasket 14. Centrally of said annular recess 21, the inner top member 13 has a circular pouring opening 22. 70

The gasket 14, preferably of compressible fibrous material, such as paper or felt, is rectangular in cross-section and is of a shape and size permitting it to fit snugly into the annular recess 21 and when placed therein it 75 is not easily disturbed.

It is of such thickness that it will slightly protrude above the central raised part 20 at the time it is positioned. When assembly is completed the gasket is compressed and presses against the 80

slide 15, in turn pressing this slide against the top member 16. All parts are thus kept in tight contact and leakage of the contents is effectively prevented. The tight contact between the parts, because of the compressible nature of the gasket, is yielding enough, 85

however, to permit the smooth operation of the sifter slide 15. The slide 15 is provided with sifter openings 23 and at each side it is depressed at 24 to provide shoulders adapted 90 to contact with two opposite points of the central raised part 20 to guide the slide in its movement and to hold it in desired relation.

The slide 15 is cut away toward the front, 95 as indicated at 25, to permit the necessary movement of the slide and to provide a forward tongue extension 26 which is turned downwardly at its end (see Fig. 4) to form a thumb piece or lip 27 for the operation of 100

the slide. At its other or rear end, the slide 15 is slit at the two points 28 and the material 29 between these slits is bent downwardly and then slightly curved upwardly to receive and hold the central straight part of a wire spring 30. This spring 30 has each end angularly bent at 31 to provide forward extensions 32 adapted to be disposed within and adjacent the angular wall 18 of the inner top member 13. This spring 30 serves to hold the slide normally in projected or closed position with the sifter perforations in the outer top member 16 out of registration with the perforations in the slide.

16 The outer top member 16 comprises a circular piece of sheet metal stamping having its central part either flat or slightly domed and provided with sifter openings 33 adapted to register with the sifter openings 23 and having a marginal flange 34 with a depending portion 35 crimped over the flange 17 of the inner member 13. Part of said flange 34 and said depending portion 35 are cut away at 36 to provide guiding clearance 23 for the tongue extension 26 of the slide 15.

When all parts have been assembled the sifter openings 23 of the slide 15 and the sifter openings 33 of the outer member 16 are out of registration. When it is desired 30 to sift the contents, pressure is exerted upon the thumb-piece 27 and the slide 15 will move inwardly against the force of the spring 30 until the perforations 23 in the slide are brought into registration with the perforations 33 in the outer top member 16. Upon releasing the thumb-piece 27 it will be evident that the slide 15 will be automatically projected outwardly and the sifter openings 33 thereby closed.

40 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

50 I claim:

1. A sifter top for containers, comprising an inner top member having a pouring opening, an outer top member having sifter openings, a perforated slide operating between said members, and a gasket interposed between the inner top member and said slide and adapted to press the slide against the top plate and prevent passage of the contents except through the sifter openings when the slide is manipulated for sifting and to hold said top member and said slide in tight yielding contact, and means for holding the gasket against sidewise movement with the slide.

65 2. A sifter top for containers, comprising an inner top member having a pouring opening, an outer top member having sifter openings, a perforated slide operating between said members, and a gasket interposed between the inner top member and said slide and adapted to prevent passage of the contents except through the sifter openings when the slide is manipulated for sifting and to hold said top member and said slide in tight yielding contact, and means for holding the gasket against sidewise movement with the slide.

ing an inner top member having a pouring opening, an outer top member having sifter openings, a perforated slide operating between said members, and a gasket interposed between the inner top member and said slide and adapted to prevent passage of the contents except through the sifter openings when the slide is manipulated for sifting and to hold said top member and said slide in tight yielding contact, and means for holding the gasket against sidewise movement with the slide.

3. A sifter top for containers, comprising an inner top member, an outer top member having sifter openings, a perforated slide located between said members, an annular recess in said inner member, a gasket located in said recess and adapted to prevent passage of the contents except through the sifter openings when the slide is manipulated for sifting and to hold said members and said slide in tight yielding contact.

4. A sifter top for containers, comprising an inner top member having an elevated part formed with a pouring opening, an outer top member having sifter openings, a perforated slide and a gasket interposed between the said top members, said gasket being adapted to prevent passage of the contents except through the sifter openings when the slide is manipulated for sifting and to hold said members and said slide in tight yielding contact, and means for holding the gasket against sidewise movement with the slide.

5. A self-closing sifter top for containers, comprising an inner top member having a raised central part with a pouring opening, an outer top member having sifter openings, a sifter slide operating between said members, an annular recess in said raised central part of the inner member, a gasket in said recess adapted to prevent passage of the contents except through the sifter openings when the slide is manipulated for sifting and to hold said members and said slide in a tight yielding contact, and a spring means connected with said slide and adapted to yieldingly hold the same in closed position.

HENRY M. NICHOLLS.
